UNITED STATES PATENT OFFICE

141,501

DESIGN FOR A NAPKIN RING

Benjamin H. Pentz and Gustav Berlin, Baltimore, Md., assignors to Wolfe & Mann Device Co., Baltimore, Md., a partnership

Application February 1, 1945, Serial No. 117,707

Term of patent 3½ years

(Cl. D44—20)

To all whom it may concern:

Be it known that we, Benjamin H. Pentz and Gustav Berlin, citizens of the United States, residing in Baltimore city, in the State of Maryland, have invented a new, original, and ornamental Design for a Napkin Ring, of which the following is a specification, reference being had to the accompanying drawing, forming part thereof, in which:

Figure 1 is a perspective view of a napkin ring showing our new design.

Figure 2 is a side elevational view thereof.

Figure 3 is a front elevational view thereof.

We claim:

The ornamental design for a napkin ring, as shown.

BENJAMIN H. PENTZ.
GUSTAV BERLIN.
